US00D991596S

(12) **United States Design Patent** (10) Patent No.: **US D991,596 S**
(45) Date of Patent: ** Jul. 4, 2023

(54) **DOG TRAINING COLLAR DEVICE**

(71) Applicant: **Shenzhen PaiPai Technology Co., Ltd,**
Guangdong (CN)

(72) Inventor: **Yuanzhuo Jiang**, Henan (CN)

(73) Assignee: **Shenzhen PaiPai Technology Co., Ltd,**
Shenzhen (CN)

(**) Term: **15 Years**

(21) Appl. No.: **29/816,126**

(22) Filed: **Nov. 18, 2021**

(51) LOC (14) Cl. **30-99**

(52) U.S. Cl.

USPC **D30/199; D10/104.1**

(58) **Field of Classification Search**

CLAIM

The ornamental design for a dog training collar device, as shown and described.

DESCRIPTION

FIG. 1 is a perspective view of a dog training collar device showing my new design;
FIG. 2 is a front view thereof;
FIG. 3 is a back view thereof;
FIG. 4 is a left side view thereof;
FIG. 5 is a right side view thereof;
FIG. 6 is a top plan view thereof; and,
FIG. 7 is a bottom plan view thereof.

1 Claim, 7 Drawing Sheets
